UNITED STATES PATENT OFFICE

108,130

DESIGN FOR A HOUSE MARKER

Woodrow Patty and Melvin Brooks, Santa Fe,
N. Mex.

Application December 6, 1937, Serial No. 73,407

Term of patent 14 years

To all whom it may concern:

Be it known that we, Woodrow Patty and Melvin Brooks, citizens of the United States of America, residing at Santa Fe, county of Santa Fe, and State of New Mexico, respectively, have invented a new, original, and ornamental Design for a House Marker, of which the following is a specification, reference being had to the accompanying drawing forming a part thereof, wherein:

We claim:

The ornamental design for a house marker, as shown.

WOODROW PATTY.
MELVIN BROOKS.
